UNITED STATES PATENT OFFICE.

RAYMOND G. BULLOCK, OF JAMESTOWN, NEW YORK, ASSIGNOR TO ART METAL CONSTRUCTION COMPANY, OF JAMESTOWN, NEW YORK, A CORPORATION OF NEW YORK.

BASE-LOCK FOR HORIZONTAL SECTIONAL UNITS.

1,036,442.

Specification of Letters Patent. Patented Aug. 20, 1912.

Application filed November 15, 1910. Serial No. 592,577.

To all whom it may concern:

Be it known that I, RAYMOND G. BULLOCK, a citizen of the United States, residing at Jamestown, in the county of Chautauqua and State of New York, have invented certain new and useful Improvements in Base-Locks for Horizontal Sectional Units, of which the following is a specification.

This invention relates to mechanism for locking drawers and is particularly adapted for use in horizontal units made of either wood or metal, which units are capable of being stacked up in a vertical series, similar to the so called well known Wernicke sectional book cases and filing cases.

The invention also relates to the construction of such units in metal.

One object of my invention is to construct a base section having a locking and controlling mechanism therein.

Another object of my invention is to construct intermediate horizontal sections capable of engaging with or being stacked up on said base section, said horizontal sections containing drawers or other filing mechanism.

Another object of my invention is to provide said horizontal sections with a locking mechanism for said drawers to prevent the opening thereof.

Another object of my invention is to make said horizontal sections interchangeable with each other and with the base section with which they are associated.

Another object of my invention is to make the locking mechanism of each section complete within itself, a part of such locking mechanism interchangeably connecting, registering and interlocking with the locking mechanisms of other sections and with the base section by which it may be controlled.

Another object of my invention is to construct the locking mechanism so as to permit the return of and the locking of individual drawers without disturbing the remaining drawers or unlocking the locking mechanism as a whole.

Another object of my invention is to cover the vertical series with a top section that will close and conceal all the locking mecha-

nism that is not concealed by the base and intermediate section.

Another object of my invention is to enable the locking mechanism of the base to operate and control all the locking mechanism of the series of sections above the base.

These and other objects of my invention will be fully described in the specification and pointed out in the claims at the end thereof.

In the accompanying drawings, Figure 1 is a perspective view of the base and a series of horizontal units thereon, with the locking mechanism therefor constructed according to my invention. Fig. 2 is a perspective detail view in skeleton form of the base lock and a portion of the locking mechanism of one of the horizontal sections. Fig. 3 is a section on the line 3^x—3^x of Fig. 5. Fig. 4 is a section on the line 4^x—4^x of Fig. 5. Fig. 5 is a horizontal section through the rear right hand corner of one of the intermediate sections, the location of the section being shown by the line 3^x—3^x of Fig. 2. Fig. 6 is a view of the interlocking shaft as it appears at the top of the intermediate section. Fig. 7 is a detail of the construction of the intermediate section showing the connection between the upright channel and the top plate. Fig. 8 is a perspective view of the part shown in Fig. 7, the top plate being omitted. Fig. 9 is a perspective view of the upright channel with the horizontal channels and drawer supporting channels connected thereto. Figs. 10 and 11 are detail views of the locking dogs. Fig. 12 is a perspective view of one of the rear upright panels which supports the locking shaft.

In the accompanying drawings, like reference numerals indicate like parts.

In the drawings reference numeral 1 indicates the base supported on four legs 2, 2 which are connected to the angle irons 3, forming the top of the base, and on which the intermediate section 4 can be placed. Mounted to slide in this base is the locking rod 5 controlled by a lock 6. The lock 6 is operated by an ordinary key and has therein the bolt which engages with the recess 7 carried in the locking rod 5. At the front the locking rod passes through an opening

in the channel 3 and at the rear passes through a bracket 8 carried on the base. Mounted on the rod 5 is a collar 9 between which and the bracket 8 a spring 10 is compressed when the rod 5 is pushed in to locked position, and by which the rod 5 is thrown out when the key is turned in the lock 6 for the purpose of locking the rod 5. At the rear end the locking bar 5 is slotted as shown 5 at 11, and with this slot engages the bell crank 12 pivoted on the base at 13. The other end of this bell crank lever engages with a connecting rod 14 which in turn engages with a crank 15 mounted on the square shaft 16 at the rear right hand corner of the base section. 10

By the reciprocation of the bar 5 the shaft 16 is oscillated through the train of mechanism above described. The shaft 16 carries at its upper end the socket 17 which socket projects slightly above the base section. Mounted at the right hand rear corner of the intermediate section 4 is the square shaft 18 which shaft 18 at its lower 20 end is provided with a square tongue 19 capable of engaging with the socket 17 on the shaft 16, so that the rotation of the shaft 16 is imparted thereby to the shaft 18. The shaft 18 likewise carries at its upper end a socket 20 similar to that shown on the upper end of the shaft 16, with which in turn engages the tongue carried on the lower end of the square shaft of the intermediate section next above it. The shaft 18 is mounted 25 to rotate in a bracket 21 supported on the intermediate section near its upper end and in the washer 22 which rests upon one of the horizontal members of the intermediate section near its lower end. A pin 23 is provided through the square shaft 18 which rests on the shoulder 22. At suitable intervals are mounted on the shaft 18 the cranks 24 having tongues 25 thereon. These tongues engage with the plates 26 keyed 30 to the square shafts 27 with which they oscillate. Each of the plates 26 is provided with a segmental slot 28 in which the tongue 25 is free to oscillate a limited amount without rocking the plate 26 on the shaft 27. 35 This permits each of the shafts 27 to have a limited motion on its own account without disturbing the position of the shaft 18 or the other shafts 27 connected therewith, the purpose for which will be described presently. One of these shafts 27 is provided 40 for each horizontal series of drawers or filing devices of the unit. In Fig. 1 I have indicated in the intermediate section nine drawers arranged in three parallel horizontal lines and in three vertical columns. One of these shafts 27 is provided for each of these three horizontal rows of drawers, one shaft serving to lock three drawers. The rear end of one of these drawers 29 is

shown in outline in Fig. 2. Each of the 65 drawers has a rectangular opening 30 cut in the back and bottom thereof, as indicated in Fig. 2, across which opening is placed the tie rod 31. On the shaft 27 immediately opposite the opening in each of the drawers 70 are placed the locking dogs 32 and 33. These dogs are alike in outline except that the dog 32 has a square hole with which it is keyed to the shaft 27, and the dog 33 has a pentagonal hole through which the shaft 75 27 passes, by means of which it has a limited rocking motion on the shaft independent thereof. The object of these dogs I am now about to describe.

When the locking bar 5 has been placed 80 in locking position the dogs 32 and 33 will be in the position shown in Fig. 2, in engagement with their respective drawers. If one of the drawers has been left out of the case it can be returned to its place and 85 locked without disturbing the position of the locking bar 5. When the drawer is pushed in the tie rod 31 will engage with the dog 32, and as it moves backward with the drawer will lift the dog 32 until the rod 31 90 passes the tip end 34 of the dog. When it has gone this far the dog will snap down into engagement with the tie rod, being impelled thereto by the operation of the spring 37 on the plate 26 and shaft 27 on which 95 said dog is mounted. One end of the spring 37 is connected to the plate 26 and the other end thereof is connected to the frame of the intermediate section. A similar spring 37 is connected on the free end of the plate 26 100 by which the shafts 27 are held each to their locking position, when the bar 5 is in the position shown in Fig. 2. While all of the dogs 32 are being lifted and the shaft 27 which carries them is being rocked by the 105 insertion of the drawer, the dogs 33 which are in engagement with the drawers that are already in locked position, are not lifted but remain in engagement with the tie rods 31, holding the drawers controlled thereby 110 securely in locked position. This is due to the lost motion between such dogs 33 and the shaft 27 as above described. Otherwise the insertion of a drawer would at a certain point temporarily unlock all of the drawers 115 in the same horizontal line therewith, due to the rocking of the shaft 27 and the lifting of the dogs carried thereby. It will be seen that the rocking of the shaft 27 sufficient to lift the dogs 32 clear of the tie rods 120 31 is not sufficient to disturb the position of the dogs 33, which dogs remain in engagement with their respective drawers.

The construction of the intermediate section in which the locking arrangement above described is carried will now be described. The intermediate section is built upon the bottom plate 40, the outer edges of which

are bent down and in to form the channel 42. At suitable points the plate 40 is perforated and through these perforations pass the reduced ends of the upright channel 41. 5 The upright channels 41 are bent of a single sheet of metal to the shape shown in cross section in Figs. 8 and 9, having lugs or reduced ends at the upper and lower ends thereof. At the side of these lugs the upper and lower end of the channel forms a shoulder. The lugs 43 pass through the plate 40 and the shoulder 44 rests against it. The channels are locked to the plate 40 by bending over the lugs 43 which are split for this purpose, one side of which is bent to the right and the other side to the left. If desired of course the lug might be left whole and perforated, in which case it could be fastened to the bottom plate by a tie 10 rod similar to that used at the top. At the top of the section is placed the plate 46, through perforations in which the reduced ends 47 of the upright channel 41 pass, which channels are locked to said plate by the rod 48 passing through suitable perforations in said reduced ends. In the sides 15 on the upright channels 41 are suitable perforations through which extend tongues 49 struck up on the supporting channels 50 by 20 which the drawers are supported. These tongues 49 pass through the channel 41 and a series of them are locked into engagement with said channel by the rod 51. The horizontal channels 52 are also provided with 25 reduced ends 53 which pass through similar perforations in the channel 41, which reduced ends 53 are in the same vertical column of the lugs 49 on the channel 50, so 30 that the same locking rod 51 passes through 35 perforations in both the lugs 49 and the reduced ends 53, holding all of these parts, 40 the supporting channel 50 and the horizontal channel 52, rigidly to the upright channel 41. The upright and horizontal 45 channels at the rear of the intermediate section are formed in the same manner and are connected together and with the supporting channels in the same manner as they are connected at the front, as heretofore described. 50 The upright channels at the corners of the section are constructed similar to the channels 41 heretofore described.

As will be noticed in Fig. 9, the sides of the channel 41 are converged, forming a 55 ridge on each side thereof against which the ends of the supporting channel 50 and the shoulders of the channels 52 bear, thus increasing the rigidity of the structure.

As indicated by Figs. 1 and 9, each 60 section is made up of a top plate 46 and a bottom plate 40 connected by eight upright channels 41, four of which channels are placed at the front and four at the back. Each pair of outside upright channels 41

is connected by three supporting channels 65 50, while each of the intermediate pairs of upright channels 41 is connected by six of the supporting channels 50. The consecutive channels in front and back are connected together by two of the channels 52, 70 or cross rails. In this manner all the members of the intermediate section are securely tied together and form a light structure of great strength and rigidity.

As shown in Fig. 7, the bottom of each of 75 the intermediate sections is provided with the angle 67 which makes a depending flange that encircles the top of the intermediate section below it or the top of the base section, and each of the intermediate sections 80 at the top is provided with a recess into which said flange or angle 67 nests, engaging therewith and thus locking the two sections together on all sides.

As shown in Fig. 12, the rock shafts 27 85 pass through the rear upright channels of the section. The channels are perforated with pentagonal holes 60, such as that shown at the top of Fig. 4, in which the rock shafts 27 can freely oscillate.

It will be seen from the foregoing description that I have provided a series of filing devices made up of horizontal sections, with a suitable base and top therefor, together with a locking mechanism for each section 95 self-contained and controlled by the operating mechanism of the base, the sections with their locking mechanism being interchangeable with each other. It will also be seen that the series is readily assembled and 100 taken apart, the parts normally going together by simply stacking the intermediate sections on top of each other and on the base, covering the whole series by the top section. As the parts are made to gage, the 105 sections with the locking mechanism will go together so that the one base lock controls the whole.

It will be obvious that the locking or controlling mechanism, instead of being placed 110 in the base, may be placed in any of the intermediate sections or in the top section, such an arrangement being obviously within the scope and spirit of my invention.

Having thus described my invention, what 115 I claim as new and patentable is as follows:

1. In a filing case, the combination of a frame work, drawers and rocking shafts supported thereby, dogs on said rock shafts engaging with said drawers to lock them, an 120 independent rocking shaft common to all of aforesaid rocking shafts and engaging therewith to oscillate them to and from rocking position, said rock shaft extending transversely to said shafts and parallel to 125 the series thereof.
2. In a filing case, the combination of a frame work, drawers and rock shafts sup-

ported thereby, dogs on said rock shafts engaging with said drawers to lock them, an independent rock shaft common to all of aforesaid rocking shafts and engaging 5 therewith to oscillate them to and from rocking position, a loose engagement between each of said first named rock shafts and the independent rock shaft permitting independent movement of any one of the first 10 named rock shafts without moving the independent rock shaft.

3. The combination in a filing case of drawers mounted to slide therein, rock shafts mounted to oscillate in the vicinity of 15 said drawers, dogs on said rock shafts engaging said drawers to lock said drawers, an operating shaft for said rock shafts extending transversely thereto and loosely engaging said rock shafts, means for oscillating 20 said operating shaft to rock said rock shafts and cause the locking or unlocking of said drawers.

4. The combination in a system of horizontal units of a base section having an operating and locking device, intermediate sections having drawers or filing devices therein, rock shafts supported adjacent to said drawers or filing devices, dogs on said rock shafts for engaging with said drawers, an 25 oscillating shaft in each section connected to said rock shafts to compel the operation thereof, said oscillating shaft extending transversely to said shafts and parallel to the series thereof, means for connecting said 30 oscillating shafts of the intermediate sections together for simultaneous movement, means connecting said oscillating shafts to the operating and locking device of the base section for operation thereby.

40 5. The combination of a series of drawer sections, locking mechanism in each drawer section for locking the drawers thereof, said locking mechanism comprising a series of rock shafts, an oscillating shaft in each section for driving said rock shafts, couplings 45 between the oscillating shafts of consecutive sections for causing said shafts to move in unison, said oscillating shaft extending transversely to said shafts and parallel to 50 the series thereof.

55 6. The combination in a filing case of a plurality of drawers therein, means for locking said drawers collectively and individually, means permitting the independent locking of a single drawer without releasing drawers that have previously been locked, said means comprising a series of horizontal rock shafts having locking dogs thereon, an upright rock shaft connected to said horizontal shafts in such manner as to oscillate them and permit a limited oscillation of any of them.

60 7. The combination in a filing device of a series of drawers and a square rock shaft ad-

jacent thereto, two dogs on said rock shaft 65 for each of said drawers, one of said dogs being closely mounted thereon and the other loosely mounted thereon, the second rock shaft extending transversely to said first named rock shaft for the purpose of rocking 70 it, a loose engagement between said rock shafts, permitting said first named rock shaft to rock far enough to disengage one set of dogs from the filing devices controlled thereby, leaving the other set of dogs in engagement with said filing devices without disturbing the position of the second rock shaft.

8. The combination in a filing case of drawers arranged in a horizontal row, a 80 rock shaft adjacent thereto, two dogs mounted on said rock shaft for each of said drawers, both of said dogs engaging with their particular drawer to lock said drawer, one of said dogs being rigidly mounted on 85 said shaft and the other dog being loosely mounted thereon, an upright rock shaft loosely engaged with said horizontal rock shaft, said horizontal rock shaft being capable of oscillating far enough to lift the 90 dogs rigidly mounted thereon out of engagement with their respective drawers without disturbing the upright rock shaft and without disengaging the dogs loosely mounted thereon from the drawers with which they 95 are in engagement.

9. The combination in a filing case, of a plurality of drawers mounted therein, a rock shaft adjacent thereto, two dogs mounted on said rock shaft for each of said drawers, one of said dogs being closely keyed to said shaft and the other of said dogs being loosely keyed to said shaft, said shaft being capable of rocking so as to disengage the 100 dogs tightly keyed thereon from their respective drawers, leaving the dogs loosely keyed thereon in engagement with their drawers.

10. The combination in a filing case, of a plurality of drawers mounted therein in a row, a rock shaft adjacent thereto, two dogs mounted on said rock shaft for each of said drawers and capable of engaging with the 110 drawers to lock them, said drawers being capable of lifting said dogs on being returned to position and being locked thereby, said parts being so arranged that upon the insertion of a drawer the dogs for locking said drawer will be moved with a rock shaft, but at least one of the dogs for each of the 120 remaining drawers in the row will remain in locked engagement with its drawer.

11. The combination in a filing case, of a plurality of drawers mounted therein in a row, a rock shaft adjacent thereto, two dogs 125 mounted on said rock shaft for each of said drawers and capable of engaging with the drawers to lock them, said drawers being

capable of lifting said dogs on being returned to position and being locked thereby, said parts being so arranged that upon the insertion of a drawer the dogs for locking said drawer will be moved with the rock shaft, but at least one of the dogs for each of the remaining drawers in the row will remain in locked engagement with its drawer, a spring for normally holding said 10 rock shaft in position to secure engagement between said dogs and their drawers.

12. The combination in a filing case of a drawer, a locking device adjacent thereto, said locking device including two dogs both 15 of which are capable of engaging with said drawer, a common means for operating said dogs, said means operating to lift one of said dogs out of engagement with the drawer before moving the other dog.

20 13. The combination in a filing case of a drawer, a locking device adjacent thereto, said locking device including two dogs both of which are capable of engaging with said

drawer, a rock shaft for operating said dogs, said shaft operating to lift one of 25 said dogs out of engagement with the drawer before moving the other dog.

14. The combination in a filing case of a drawer, a locking device adjacent thereto, said locking device including two dogs both 30 of which are capable of engaging with said drawer, an angular hole in each of said dogs, the hole in one being considerably larger than the other, a rock shaft passing through said holes and making a close fit with the 35 dog having the small hole and a loose fit with the dog having the large hole, said shaft operating to lift said dogs successively out of engagement with said drawer.

In testimony whereof I affix my signature 40 in presence of two witnesses.

RAYMOND G. BULLOCK.
